UNITED STATES PATENT OFFICE.

WILLIAM TEEGARDEN, OF HIGGINSPORT, OHIO, ASSIGNOR OF ONE-HALF
HIS RIGHT TO GEORGE TEEGARDEN, OF SAME PLACE.

IMPROVEMENT IN HUBS FOR VEHICLE-WHEELS.

Specification forming part of Letters Patent No. 159,123, dated January 26, 1875; application filed
July 11, 1874.

To all whom it may concern:

Be it known that I, WILLIAM TEEGARDEN, of Higginsport, county of Brown and State of Ohio, have invented certain Improvements in Hubs for Wheels, of which the following is a specification:

My invention relates to hubs of wheels for vehicles; and consists in the arrangement and use of one or more sets of friction-rollers in a wheel-hub for the purpose of lessening the friction between the axle and wheel, and of dispensing with the use of lubricating-oils.

Figure 1 is a perspective view of my improved hub. Fig. 2 is a longitudinal section through the middle of the same. Fig. 3 is an end view of the same.

D is a square wooden hub, into which spokes are tenoned or otherwise secured at d. On each end of the hub D is a broad metal band, E, which overlaps the said hub sufficiently to permit of lugs C being fastened to it. These lugs are arranged in pairs around the inside of the bands E. Between the lugs of each pair is a small pulley or friction-roller, B, ar-

ranged as shown in the drawing. Any number of such rollers greater than two may be used, though I have shown four in my drawing. The axle A of the vehicle passes between and is supported upon these rollers B, which are so adjusted as to support the entire weight of the axle and keep the same out of contact with the hub. As will be readily seen, the friction between axle and wheel is thus reduced to a minimum, and the use of oil, which so often freezes or dries up, or catches dirt, is entirely done away with.

I do not claim, broadly, the use of friction-rollers in a wheel-hub, as I am aware that they have been used before; but

What I do claim as my invention is—

A wooden hub, in combination with lugs C and friction-rollers B B, substantially as shown and described.

WILLIAM TEEGARDEN.
